UNITED STATES PATENT OFFICE

162,277

STOCKING

Leonard J. Accardi, Brooklyn, N. Y.

Application December 28, 1949, Serial No. 6,865

Term of patent 3½ years

(Cl. D47—7)

To all whom it may concern:

Be it known that I, Leonard J. Accardi, a citizen of the United States, residing in Brooklyn, in the county of Kings and State of New York, have invented a new, original, and ornamental Design for a Stocking, of which the following is a specification, reference being had to the accompanying drawing, forming part thereof.

In the drawings,

Fig. 1 is a side elevational view of a lady's stocking; and Fig. 2 is an enlarged view of the toe section shown in Fig. 1 embodying my new design which consists of angularly arranged rows of tight and loose courses forming an open-work band adjacent to the toe as shown.

I claim:

The ornamental design for a lady's stocking, as shown and described.

LEONARD J. ACCARDI.
